Homer Niederhauser, Berne, Ind.

Application February 6, 1953, Serial No. 335,420

6 Claims. (Cl. 155—116)

The present invention relates to a mechanical chair, and more particularly to a chair having a backrest which is positionable between full upright and reclined positions.

Many different types of mechanical chairs in which the backrest is movable to full reclining position have been proposed and used; however, certain disadvantages are inherent in these prior art designs, which include the disadvantage of the backrest not conforming to the movement of an individual's torso as he moves backwardly or forwardly with the backrest. This unnatural movement is easily detected by sitting in a prior art chair with the backrest in full upright position, then allowing the backrest to swing backwardly with the individual maintaining relaxed contact therewith. As the back swings downwardly, a relative motion occurs between the backrest and the individual which is evidenced by the individual's clothes being drawn or gathered uncomfortably upwardly. This requires that the individual lean forwardly sufficiently to allow his clothes to readjust. By analyzing this relative motion between the backrest and the individual, it has been discovered that the motion of the backrest is unnatural, meaning that the backrest motion does not conform to that of the motion of an individual's back as he swings from an upright sitting position to a full reclining position.

It is therefore an object of this invention to provide a mechanical chair having relatively movable backrest and seat portions which are movable from full sitting to full reclining position and which conforms substantially to the motion of an individual's torso between full sitting and full reclining position.

It is another object of this invention to provide a mechanical chair having a backrest which is positionable between full sitting and full reclining positions and which may be comfortably operated by an individual by merely exerting operating force on the backrest.

Other objects will become apparent as the description proceeds.

To the accomplishment of the above and related objects, my invention may be embodied in the forms illustrated in the accompanying drawings, attention being called to the fact, however, that the drawings are illustrative only, and that specific change may be made in the specific constructions illustrated and described, so long as the scope of the appended claims is not violated.

In the drawings:

Fig. 1 is a perspective view of a typical chair of this invention;

Fig. 2 is a top plan cut-away view of the chair of Fig. 1 showing the mechanism therein;

Fig. 3 is a perspective illustration of a part of the mechanism for operating the chair; and

Figs. 4, 5 and 6 are side elevations of the same chair with the fabric covering removed showing the chair adjusted to full sitting, intermediate reclining, and full reclining positions.

With reference to the drawings, and more particularly to Fig. 1, a typical chair which may incorporate this

2

invention is shown as being of the overstuffed design, but it will of course be understood, that any chair having a seat and backrest may be designed to incorporate the operating features of this invention. The chair comprises a stationary frame generally indicated by the reference numeral 10, a seat 12 and a swingable backrest 14. The frame 10 is so designed as to provide two upright support members 16 at the rear thereof (one such support 16 being shown in Fig. 3) which must be of a suitable strength and rigidity as will become apparent from the following description. A pivot plate 18 is mounted on the inner lateral side of the frame support 16, and in quality merchandise, will be preferably fabricated of sheet metal. A cantilever 20 is pivoted at A to the plate 18 and extends forwardly toward the front of the chair. A lever 22 is pivoted intermediate its ends to a point B on the cantilever 20 intermediate the latter's ends. Another common lever 24 is pivoted intermediate its ends at C to the plate 18 so as to lie in the general plane of the two levers 20 and 22. A support plate 26 having suitable fastening apertures 28, is fixedly secured to the left end of the common lever 22 and projects inwardly of the chair at right angles to the general plane of levers 20, 22, 24. As seen more clearly in Figs. 4, 5 and 6, this backrest support 26 is set at an acute angle on the lever 22.

Further describing the leverage system, a link 30 pivotally connects the adjacent ends of the left-hand lever arms of the two levers 22 and 24 together, and a similar link 32 pivotally connects the adjacent ends of the opposite lever arms together also. As will become apparent from the description to follow, one or the other of these two links 30 and 32 may be removed without altering the operation of the system.

A third link 34 connects the right-hand end of the two levers 20 and 24 together, and a depending strap 46 is connected at its upper extremity to the outer or right-hand end of the lever 22. It will, of course, be understood that the linkage mechanism just described is duplicated on the opposite side of the chair as illustrated more clearly in Fig. 2, with the lower extremities of the two depending straps 36 being tied together by means of a horizontally extending strap 38 having suitable pivot connections 40. This strap 38 passes underneath the rear portion of the seat 12 for swinging the seat about suitable hinges 42 mounted between the front edge of the seat 12 and the chair frame 10. As is shown more clearly in Figs. 4, 5 and 6, the backrest 14 is rigidly mounted on the support 26 of the lever 22. Also as shown in Figs. 4, 5 and 6, the seat 12 is shown as being comprised of suitable conventional springs and pads indicated by dashed lines at 44 and 46 respectively. The seat surface is indicated by the reference numeral 48.

With the backrest in full upright position, the operating linkage will conform substantially to that shown in Figs. 3 and 4. With the backrest swung to a position approximately midway between full sitting and reclining positions, it will assume the position illustrated in Fig. 5. In Fig. 6, the backrest and seat are moved to full reclining or horizontal positions.

The operation of the leverage system is as follows: Starting from a full sitting position, and exerting a slight force on the upper part of the backrest 14 sufficient to swing it backwardly, the lever 22 will be swung counterclockwise about the pivot B. This motion is transmitted to the common lever 24 by means of the strut link 30 causing the lever 24 to rotate counterclockwise about its pivot C. The right end of the lever 24 now moves upwardly carrying with it the right end of the cantilever 20, this motion transfer occurring through the intermediary of the second strut link 34. The link 32 follows the corresponding motion of the respective right-hand ends

of the levers 22 and 24. Since the right end of the cantilever 20 swings upwardly, the rear of the seat 12 will be lifted about its fulcrum 42 by reason of the upward motion of the sling comprised of the straps 36 and 38. If continued force is exerted on the upper portion of the backrest 14, the latter may be forced to its full reclining position, as illustrated in Fig. 6, the seat 12 swinging upwardly an amount sufficient to bring the seat surface 48 into substantial horizontal alignment with the upper surface of the backrest 14.

Now if the links and levers are made to correspond to the sizes as indicated in the drawings, the seat 12 and the backrest 14 will move relative to each other in directions which substantially conform to the movement of a person's body thereby making the feeling of reclining in the chair completely natural and comfortable without the usual gathering or slipping of the person's clothes. The motion of the backrest may be easily plotted by the use of geometry and it will be found that such plot will show generally that the backrest 14 moves longitudinally downwardly as it is being swung backwardly while the lower extremity is simultaneously describing an arc in a downward and forward direction. This motion of the backrest may be more easily envisaged by considering the path of movement of the point of intersection or attachment between the backrest support 26 and the left end of the lever 22. Considering Figs. 4 and 5, as the backrest 14 is swung rearwardly, the motion of the lever 22 is transformed into a leverage reaction which swings the outer end of the lever 20 upwardly. This results in the pivot point B being swung upwardly, and with the point B being below the pivot point A as shown, the support 26 will move generally forwardly as well as downwardly.

The exact path of movement of the backrest 14, and the seat 12 as well, will depend upon the lengths of the respective lever arms and the points of connection between the levers and the respective links. However, by making a geometric analysis of the swinging motion of the human body as it moves from full sitting to full reclining positions, it is possible to arrange the leverage system to conform substantially thereto. An analysis shows that by varying the relative positions of the connections between the link 34 and the levers 20 and 24, the distance through which the back support 26 travels may be varied. The path followed by the backrest support 26 is partially dependent upon the position of pivot B on the cantilever 20 and the links of the lever arms of lever 22. A general analysis shows that as the lever 22 is swung counterclockwise, the sling 36, 38 moves upwardly. Therefore, more or less mechanical advantage as desired, in operating the chair may be gained by adjusting the sizes of the lever arms of the lever 22, lengthening the left-hand lever arm serving to increase the mechanical advantage.

While the sling 36, 38 has been shown as being fastened to the outer extremity of the cantilever 20, the system will operate equally satisfactorily by fastening the upper ends of the straps 36 to the right-hand end portions of the lever 24. The only requirement in this respect is that the movement of the seat 12 be made to comfortably conform to the movement of the backrest 14 and hence the movement of the human body.

As is apparent from the foregoing description, the backrest 14 may be operated either upwardly or downwardly by exerting a corresponding force on the backrest 14. Ease of operation may be adjusted by introducing friction at the various joints and pivots in the leverage system, as well as adjusting the leverage ratios of the leverage system.

While the exact motion of the chair parts will vary with design preferences, the means is hereby presented under this invention by which suitable, body-conforming motion may be built into a mechanical chair.

Another possible alternative to the structure illustrated

in the drawings is one in which the link 30 is cut off adjacent the pivot B and the link 34 is eliminated, the strap 36 being affixed to the lever 24 a suitable distance to the right of pivot C.

Design and operational preferences will dictate the lengths of the various levers and links in order to achieve the desired character of relative movement between the backrest and the seat.

What is claimed is:

- 10 1. A mechanical chair comprising a seat and a backrest which are movable relative to each other into full sitting or full reclining position, a stationary support, a system of levers pivotally carried by said support and operatively connecting said seat and backrest together, 15 said system of levers including a first cantilever pivoted at one end on said support, a second lever pivoted intermediate its ends on said cantilever and being fixedly secured to said backrest, leverage means interconnecting one end of said second lever with the outer end of said cantilever, and means operatively connecting said cantilever to said seat whereby said seat exerts a gravitational force on said cantilever, said system of levers being operable to swing the backrest from upright to reclining position in accordance with a motion which carries the 20 lower end of the backrest downwardly and forwardly while the backrest itself is moving longitudinally downwardly.

2. A mechanical chair comprising a seat and a backrest which are movable relative to each other into full 30 sitting or full reclining position, a stationary support, a system of levers pivotally carried by said support and operatively connecting said seat and backrest together, said system of levers including a first cantilever pivoted at one end on said support, a second lever pivoted intermediate its ends on said cantilever and being fixedly secured to said backrest, leverage means interconnecting one end of said second lever with the outer end of said cantilever to said seat whereby said seat exerts a gravitational force on said cantilever, said system of levers being operable to swing the backrest from upright to reclining position in accordance with a motion which carries the 35 lower end of the backrest downwardly and forwardly while the backrest itself is moving longitudinally downwardly.

3. A mechanical chair comprising a seat and a backrest which are movable relative to each other into full sitting or full reclining position, a stationary support, a system of levers pivotally carried by said support and operatively connecting said seat and backrest together, 40 said system of levers including a first cantilever pivoted at one end on said support, a second lever pivoted intermediate its ends on said cantilever and being fixedly secured to said backrest, a third lever pivoted intermediate its ends to said support, a first rigid link interconnecting two adjacent ends of said second and third levers together whereby clockwise motion of one will impart clockwise motion to the other, a strut interconnecting the outer end of said cantilever with the adjacent end of said third lever whereby both levers will move together in the same rotational direction, and linkage means operatively coupled between the outer end of said cantilever and said seat, said system of levers thereby being operable to swing the backrest from upright to reclining position in accordance with a motion which carries the lower end of the backrest downwardly and forwardly while the backrest itself is moving longitudinally downwardly.

4. A mechanical chair comprising a seat and a backrest which are movable relative to each other into full sitting or full reclining position, a stationary support, a system of levers pivotally carried by said support and operatively connecting said seat and backrest together, 45 said system of levers including a first cantilever pivoted at one end on said support, a second lever pivoted intermediate its ends on said cantilever and being fixedly secured to said backrest, a third lever pivoted intermediate its ends to said support, a first rigid link interconnecting two adjacent ends of said second and third levers together whereby clockwise motion of one will impart clockwise motion to the other, a strut interconnecting the outer end of said cantilever with the adjacent end of said third lever whereby both levers will move together in the same rotational direction, and linkage means operatively coupled between the outer end of said cantilever and said seat, said system of levers thereby being operable to swing the backrest from upright to reclining position in accordance with a motion which carries the lower end of the backrest downwardly and forwardly while the backrest itself is moving longitudinally downwardly.

5. A mechanical chair comprising a seat and a backrest which are movable relative to each other into full sitting or full reclining position, a stationary support, a system of levers pivotally carried by said support and operatively connecting said seat and backrest together, 50 said system of levers including a first cantilever pivoted at one end on said support, a second lever pivoted intermediate its ends on said cantilever and being fixedly secured to said backrest, a third lever pivoted intermediate its ends to said support, a first rigid link interconnecting two adjacent ends of said second and third levers together whereby clockwise motion of one will impart clockwise motion to the other, a strut interconnecting the outer end of said cantilever with the adjacent end of said third lever whereby both levers will move together in the same rotational direction, and linkage means operatively coupled between the outer end of said cantilever and said seat, said system of levers thereby being operable to swing the backrest from upright to reclining position in accordance with a motion which carries the lower end of the backrest downwardly and forwardly while the backrest itself is moving longitudinally downwardly.

6. A mechanical chair comprising a seat and a backrest which are movable relative to each other into full sitting or full reclining position, a stationary support, a system of levers pivotally carried by said support and operatively connecting said seat and backrest together, 55 said system of levers including a first cantilever pivoted at one end on said support, a second lever pivoted intermediate its ends on said cantilever and being fixedly secured to said backrest, a third lever pivoted intermediate its ends to said support, a first rigid link interconnecting two adjacent ends of said second and third levers together whereby clockwise motion of one will impart clockwise motion to the other, a strut interconnecting the outer end of said cantilever with the adjacent end of said third lever whereby both levers will move together in the same rotational direction, and linkage means operatively coupled between the outer end of said cantilever and said seat, said system of levers thereby being operable to swing the backrest from upright to reclining position in accordance with a motion which carries the lower end of the backrest downwardly and forwardly while the backrest itself is moving longitudinally downwardly.

7. A mechanical chair comprising a seat and a backrest which are movable relative to each other into full sitting or full reclining position, a stationary support, a system of levers pivotally carried by said support and operatively connecting said seat and backrest together, 60 said system of levers including a first cantilever pivoted at one end on said support, a second lever pivoted intermediate its ends on said cantilever and being fixedly secured to said backrest, a third lever pivoted intermediate its ends to said support, a first rigid link interconnecting two adjacent ends of said second and third levers together whereby clockwise motion of one will impart clockwise motion to the other, a strut interconnecting the outer end of said cantilever with the adjacent end of said third lever whereby both levers will move together in the same rotational direction, and linkage means operatively coupled between the outer end of said cantilever and said seat, said system of levers thereby being operable to swing the backrest from upright to reclining position in accordance with a motion which carries the lower end of the backrest downwardly and forwardly while the backrest itself is moving longitudinally downwardly.

8. A mechanical chair comprising a seat and a backrest which are movable relative to each other into full sitting or full reclining position, a stationary support, a system of levers pivotally carried by said support and operatively connecting said seat and backrest together, 65 said system of levers including a first cantilever pivoted at one end on said support, a second lever pivoted intermediate its ends on said cantilever and being fixedly secured to said backrest, a third lever pivoted intermediate its ends to said support, a first rigid link interconnecting two adjacent ends of said second and third levers together whereby clockwise motion of one will impart clockwise motion to the other, a strut interconnecting the outer end of said cantilever with the adjacent end of said third lever whereby both levers will move together in the same rotational direction, and linkage means operatively coupled between the outer end of said cantilever and said seat, said system of levers thereby being operable to swing the backrest from upright to reclining position in accordance with a motion which carries the lower end of the backrest downwardly and forwardly while the backrest itself is moving longitudinally downwardly, said seat rising during the downward swing of said backrest.

9. A mechanical chair comprising a seat and a backrest which are movable relative to each other into full sitting or full reclining position, a stationary support, a system of levers pivotally carried by said support and operatively connecting said seat and backrest together, 70 said system of levers including a first cantilever pivoted at one end on said support, a second lever pivoted intermediate its ends on said cantilever and being fixedly secured to said backrest, a third lever pivoted intermediate its ends to said support, a first rigid link interconnecting two adjacent ends of said second and third levers together whereby clockwise motion of one will impart clockwise motion to the other, a strut interconnecting the outer end of said cantilever with the adjacent end of said third lever whereby both levers will move together in the same rotational direction, and linkage means operatively coupled between the outer end of said cantilever and said seat, said system of levers thereby being operable to swing the backrest from upright to reclining position in accordance with a motion which carries the lower end of the backrest downwardly and forwardly while the backrest itself is moving longitudinally downwardly.

10. A mechanical chair comprising a seat and a backrest which are movable relative to each other into full sitting or full reclining position, a stationary support, a system of levers pivotally carried by said support and operatively connecting said seat and backrest together, 75 said system of levers including a first cantilever pivoted at one end on said support, a second lever pivoted intermediate its ends on said cantilever and being fixedly secured to said backrest, a third lever pivoted intermediate its ends to said support, a first rigid link interconnecting two adjacent ends of said second and third levers together whereby clockwise motion of one will impart clockwise motion to the other, a strut interconnecting the outer end of said cantilever with the adjacent end of said third lever whereby both levers will move together in the same rotational direction, and linkage means operatively coupled between the outer end of said cantilever and said seat, said system of levers thereby being operable to swing the backrest from upright to reclining position in accordance with a motion which carries the lower end of the backrest downwardly and forwardly while the backrest itself is moving longitudinally downwardly.

rest which are movable relative to each other into full sitting or full reclining position, a stationary support, a system of levers pivotally carried by said support and operatively connecting said seat and backrest together, said system of levers including a first cantilever pivoted at one end on said support, a second lever pivoted intermediate its ends on said support, a second lever pivoted intermediate its ends on said cantilever and being fixedly secured to said backrest, a third lever pivoted intermediate its ends to said support, a first rigid link interconnecting two adjacent ends of said second and third levers together whereby clockwise motion of one will impart clockwise motion to the other, a strut interconnecting the outer end of said cantilever with the adjacent end of said third lever whereby both levers will move together in the same rotational direction, and linkage means operatively coupled between the outer end of said cantilever and said seat, said system of levers thereby being operable to swing the backrest from upright to reclining position in accordance with a motion which carries the lower end of the backrest downwardly and forwardly while the backrest itself is moving longitudinally downwardly.

5. A mechanical chair comprising a seat and a backrest which are movable relative to each other into full sitting or full reclining position, a stationary support, a system of levers pivotally carried by said support and operatively connecting said seat and backrest together, said system of levers including a first cantilever pivoted at one end on said support, a second lever pivoted intermediate its ends on said cantilever and being fixedly secured to said backrest, a third lever pivoted intermediate its ends to said support, first and second links inter-

5

connecting adjacent respective ends of said second and third levers together whereby clockwise motion of one will impart clockwise motion to the other, a strut interconnecting the outer end of said cantilever with the adjacent end of said third lever whereby both levers will move together in the same rotational direction, and linkage means operatively coupled between the outer end of said cantilever and said seat, said system of levers thereby being operable to swing the backrest from upright to reclining position in accordance with a motion which carries the lower end of the backrest downwardly and forwardly while the backrest itself is moving longitudinally downwardly.

6. A mechanical chair comprising a seat and a backrest which are movable relative to each other into full sitting or full reclining position, a stationary support, a system of levers pivotally carried by said support and operatively connecting said seat and backrest together, said system of levers including a first lever pivotally mounted on said support and having an operative connection with said seat, a second lever pivotally mounted on said first lever and carrying said backrest, means interconnecting said first and second levers together for transmitting motion from said second lever to said first lever, said system of levers being operable to swing the backrest from upright to reclining position in accordance with a motion which carries the lower end of the backrest downwardly and forwardly while the backrest itself is moving longitudinally downwardly.
